AXIAL FLOW COMPRESSOR AND LIKE MACHINES

Joseph Stanley Hall, Sale, England, assignor to
 Metropolitan-Vickers Electrical Company Limited, London, England, a company of Great Britain

Application January 13, 1944, Serial No. 518,181
 In Great Britain January 21, 1942

Section 1, Public Law 690, August 8, 1946
 Patent expires January 21, 1962

18 Claims. (Cl. 230—123)

1

This invention relates specifically to axial flow compressor or turbine type machines, or sections of machines, of the kind having a plurality of consecutive intercalated rows or stages of mutually co-operating relatively rotating substantially radial blading carried by two generally cylindrical members arranged one within the other and of different diameters to provide between them an annular passage along which the elastic or inelastic fluid, acted upon by the blading therein or acting upon it, is progressively impelled or compressed or expanded (or decompressed) so that, at least in the case of elastic fluid, the sectional area of said passage may, and usually will, change progressively along its length. One of such blade-carrying cylindrical members may be stationary, in which case it is more conveniently, but not necessarily, the inner one which rotates, the blading carried by the outer member then constituting guide blading. Alternately the two blade-carrying members may rotate in opposite directions providing a contra-rotational arrangement. The two generally cylindrical blade-carrying members will be hereinafter for convenience called "rotors," and contra-rotational arrangements only of air compressors will be considered in detail, but it is to be understood that the invention includes within its scope arrangements wherein either "rotor" may be fixed.

The present invention is applicable in general to any axial flow machine as above specified dealing with any fluid and to the following machines in particular by way of example, namely high pressure and exhaust turbines for steam or gas; air, vapour or gas compressors, superchargers, fans; and even liquid pumps or turbines; and it is applicable to combinations of such apparatus.

The invention, however, is notably concerned with the high efficiency, high speed air compressors of internal combustion or gas turbine plants primarily for the propulsion of aircraft or other craft.

The invention is also applicable to combinations of apparatus forming an internal combustion power plant such as, for example, the augmentor apparatus which per se forms the subject matter of U. S. application Serial No. 518,165, filed of even date herewith. That is to say, the present invention is further applicable to apparatus having two or more tiers of blading carried by coaxial "rotors" disposed within one another, for example a multi-stage air compressor surrounding a multi-stage gas turbine, or a single multi-stage rotary machine in which some of the

blading is arranged as an outer or inner tier, and the remainder in one or more successive coaxial tiers arranged radially outside or inside the first tier. It will be understood that the several coaxial blade-carrying members can be interconnected in various ways according to the requirements of the design and that any of the simple or composite elements so formed may be allowed to rotate, or remain stationary, as desired.

- 5 10 15 20 25 30 35 40 45 50 55
- It will be appreciated that by reason of the high speed of rotation of the rotors and of the high duty of the rotary members of gas turbine plant every part thereof must be accurately and rigidly located, with the rotors truly coaxial and accurately balanced. In arrangements wherein the outer rotor is rotating it is desirable that it should rotate at the highest practicable speed, so that this rotor cannot be constructed in halves, that is, split on a diametrical plane, for the purpose of enabling it to be assembled, in the well known manner, around the finished inner rotor. However, the invention has advantages in arrangements wherein the "outer rotor" is split and need not rotate.
- Particularly when the gas turbine plant is for the propulsion of aircraft, where the weight of and the volumetric space occupied by the plant must be reduced to reasonable minima, the carrying out of the construction of the plant has presented, and still presents, many problems, particularly regarding the compressors or like machines with which the present invention is more particularly but not exclusively concerned. There may be mentioned by way of example the problems of mechanical strength, rigidity, reliability, ease and rapidity of assembly and facility for mass production, as well as the provision and location of the ball or other bearings of the rotating members and the driving connections thereof.

In the case more particularly of the multi-stage air compressors or like machines a very important problem is a construction enabling the blade-carrying rotors to be assembled. In this respect two different general methods and arrangements have inter alia been described in the specifications of prior U. S. applications Serial Nos. 518,167 and 518,168 filed of even date herewith, now abandoned, both arrangements involving the construction of the consecutive blading rows or stages on separate foundation members which are consecutively assembled in line, with the provision of spacing rings or distance members and keying and/or other torque transmitting means

so that the intercalated rows of blading of each group are built up consecutively into respective oppositely or relatively rotating "rotors." In the specification of said U. S. application Serial No. 518,168 the compressor blading of each row, except the end rows, is carried in or on the centre part of a foundation ring which integrally constitutes also the spacing ring, the rings being slid into and on to outer and inner continuous relatively thin-walled cylinders alternately, to constitute the two rotors. In the specification of said U. S. application Serial No. 518,167 the two multi-stage rotor cylinders of a turbine driving a compressor are themselves progressively built up together of aligned cylindrical sections which may be bolted together and/or riveted and/or welded together one after the other, there being in this case no continuous cylinders receiving foundation rings.

In either case it is, in some arrangements of the plant, necessary to drive the outer rotor from one or both of its ends. In general there are several torque-transmitting circumferential joints in the rotor, whilst special apparatus is necessary for ensuring that the two rotors which become interlocked together on assembly shall be truly concentric and accurately balanced.

The present invention comprises the manufacture of a machine of the kind specified, wherein each of the relatively rotating rotors, or sections thereof, are individually fully bladed and assembled, the one separate from the other, with at least two of the relatively rotating rows or stages of blading having such form and pitch that they can be mutually "interthreaded," then assembling together the thus bladed rotors involving the movement of the one into the other in the mainly axial direction.

Since it is in many cases necessary or desirable for the outer rotor to have bearing means at each end the construction in this case involves that there must be some, and in general there need be no more than one, circumferential joint in the outer rotor, and that the blading in each of the stages or rows which pass through one another in the process of mutually inserting in an axial direction one rotor into the other not only has the same number of blades but the blades have such appropriate form and pitch that the blades of these rows can be passed between one another. With the arrangement according to the invention it is, of course, not possible to have shrouding of the type which is fixed to the blade tips, but this, in fact, is not required since the rotor cylinders themselves can in general form the boundary surface of the fluid passage. Those rows of blades which pass each other during the assembly must also either be in line or have uniform angular advance when viewed along the axis of the machine, and for this reason it is convenient to mount the blades in continuous rectilinear or spiral grooves in the rotors such as in accordance with British application No. 5,942 of 1941. Where the blades in both rotors are of the same section the clear spaces between the blades must be at least equal to half a pitch on any diameter.

Since the outer rotor encloses the inner one, the first and last rows of blades of the machine are preferably carried by the outer rotor especially when the latter is a rotating one. Since even if the circumferential joint is at one end of this rotor these first and last rows of blading do not or need not pass between any other rows of blading in the course of assembly, there is no restriction as to the form or pitch or size of these end

rows of blading. However, the circumferential joint need not be at one end of the outer rotor. It may in fact be anywhere between the ends of the rotor whereby it becomes possible to incorporate 5 blades of two further different forms and pitches along the length of the compressor. This will be appreciated from the fact that if the circumferential joint is, say, near the middle of the outer rotor then the two parts can be separately assembled around the inner rotor from opposite ends thereof so that fewer rows of blading have to pass between one another during the longitudinal shifting of said two parts into position.

It is to be appreciated that the actual shape of the air passage through the compressor in longitudinal section may be considerably varied. Either rotor cylinder providing the boundary wall of the air passage, or either portion of the divided one, may be truly cylindrical, and the other one of 15 truly conical or of flaring shape, or both or all may be conical or flaring. Certain conditions, however, have to be met. Thus when the circumferential joint is so located that in the process of 20 intercalating the blades of the inner and outer rotors the blade row or rows on both portions of the divided rotor pass blades on the undivided rotor in bringing together the two divided portions, then considering the cylindrical, conical or shaped surfaces from which the blades project, 25 namely outwardly from the inner and inwardly from the outer surface, and considering the variation in diameter of each of these two surfaces of revolution as the transverse plane under consideration moves from that of the joint towards the 30 end of the compressor in either direction, the requirement to be met is that on neither rotor may this surface increase in diameter from the joint towards the end, up to the position of the last row of blades which has been passed by a row on the other rotor. When the circumferential joint 35 is located so that to the one side of it the blade rows of the two rotors do not have to pass one another axially during the assembly process the 40 restrictions on diameter apply to the structure in the direction of the other portion only. It is on these considerations and the required heights of 45 blading that the shape of the passage is determined.

It is to be understood that the circumferential 50 joint above referred to is of such design and proportions that it can be made and broken without affecting the accuracy of the balance of the rotor. The rotors are completely bladed, assembled and balanced. The outer one is then divided and 55 threaded on to the inner, and the joint remade. Nothing has been done to affect the balance of the inaccessible inner rotor, and if any adjustments are required to the outer rotor, they are simple and readily made.

It will be also appreciated that since there is 60 only one such circumferential joint the size of the flanges or scantlings required for providing the joint need not involve a material increase in the weight of the compressor. Actually there is no 65 objection to the provision of further circumferential joints of a permanent nature, since these can be made of smaller dimensions such as by the employment of rivets or welding. The provision of such further joints need not introduce any 70 structural difficulty, because the rotors can be balanced and adjusted independently after the joints have been permanently made.

It will be understood that where the circumferential joint is located at either end of the outer 75 rotor the latter then comprises a main portion

carrying all the inwardly projecting blading except that of the first or of the last row, this being carried by the other portion of the rotor, which is jointed to said main portion.

According to another aspect of the present invention the aforesaid feature of interthreading is applied to constructions of axial flow machines with single or multiple blading tiers, at least one of the rotors of which is connected at one end only to its driving shaft or the shaft which it drives, such as by substantially radial or conical discs, sometimes through annular "swan-neck" members which give flexibility. In such case there need be no non-permanent circumferential joint in any rotor, though there may be and usually will be permanent joints, that is joints which are required for the construction of the individual rotors or stators, but which thereafter remain permanently jointed-up, and play no part in the assembly or dismantling of the machine.

The accompanying drawings illustrate somewhat diagrammatically in conventional form (except Figures 2 and 3), the upper halves in sectional elevation, several contra-rotational arrangements of machines according to the invention:

Figure 1 showing a typical simple arrangement; Figure 2 is an end elevation, and

Figure 3 a sectional plan view illustrating the form and pitch of blading appropriate for the interthreading thereof.

Figures 4 to 9 show modifications of the arrangement shown in Figure 1, and

Figs. 10 to 14 show typical multi-tier arrangements.

In Fig. 1 is represented a contra-rotational air compressor or supercharger, the annular passage of which has its walls formed, as an example, by the outer hollow cylinder member 1 and the inner slightly conical cylinder member 2, the direction of air flow being indicated by the arrows. In the example there are in all eleven rows or stages of blading, I to XI, of which the odd-numbered stages are carried by the outer rotor cylinder 1 and the even-numbered stages by the inner rotor cylinder 2.

In the arrangement shown in Fig. 1, as in all the other illustrated arrangements, it may be assumed for convenience that the blades are provided with individual roots of dovetail or equivalent form held in longitudinal or helical grooves of corresponding dovetail or like form in the members 1 and 2, as indicated by the dotted lines 3. The blades of the stages II to X inclusive have respective inner and outer roots only, the blade tips being unshrouded and being sufficiently adjacent the inner and outer walls of the rotor members 1 and 2. The blading of stages I to XI, however, has substantially radially inner foundation rings 12 and 13 respectively which are connected to or integral with discs or wheels 14 and 15. The inner rotor member 2 has attached to it or integral with it at its left-hand end a disc member 16 and at its right-hand end a disc member 17. At 18 is shown a stationary member constituting the inner wall of the annular air inlet to the compressor, this member being supported in any convenient manner and being integral with or connected to a disc member 19 which carries the outer races of ball bearings 20 and 21. The inner race of the ball bearing 20 is carried by a short shaft 22 having at its right-hand end a flange which is rigidly connected with the inner periphery of the disc member 16 whereby to provide an anti-friction bearing for the left-hand end of the inner rotor member 2. The inner

race of the bearing 21 is carried on a cylindrical extension of the disc member 14 whereby to provide correspondingly an anti-friction bearing for the left-hand end of the outer rotor member 1 of the compressor. The disc members 15 and 17 at the right-hand end of the rotor members 1 and 2 can be assumed to be connected to driving members 23 and 24, which may be, for example, sleeve shafts carried by appropriate bearings (not shown), the members 23 and 24 being shown fragmentarily in dotted lines. It will be understood, however, that the rotor members 1 and 2 may be carried at their right-hand ends on additional bearings similar to the bearings 20 and 21 provided for the left-hand end of these rotor members.

At the right-hand end of the rotor cylinder member 1 is a flange 25 secured by bolts or screws (not shown) to a flange 26 on an outer ring 27 in grooves in which radially outer roots of the blades of the stage 1 are engaged.

It will be appreciated that the non-permanent joint at the flanges 25 and 26 is made after the inner rotor member 2 has been pushed from the left-hand end into the rotor member 1, involving the inter-threading of the blading of the stages IV, VI, VIII and X of the inner rotor between the blading of the stages III, V, VII and IX of the outer rotor. After this part of the process of assembly the disc 15 carrying the blading stage XI and rings 13 and 27 is fitted into position and the flanges 25 and 26 bolted together, the bearings being also assembled. It will be appreciated that, as hereinbefore set forth, the blading of stages I and XI will not have undergone interthreading, so that these stages may have a different design and pitch from those of stages III to X, which must conform to the requirement permitting the inter-threading as illustrated by way of example by Figs. 2 and 3, which need no description beyond stating that the arrow 28' indicates that the space as viewed in the axial direction between the consecutive blades, such as VI and VIa in one row carried by the inner rotor member 2, must be not less than half-pitch to permit the blading VII, for example, carried by the outer rotor member 1 to pass between the blades VI and VIa.

The arrangement shown in Fig. 4 differs only from the arrangement shown in Fig. 1 in that it is the inner rotor cylinder 2a which is truly cylindrical, whilst it is the outer rotor cylinder 1a which is conical. It will be appreciated that the actual surfaces of members such as 1 and 2, 1a and 2a may be curvilinear to provide the necessary "flaring" by which the progressive change in the sectional shape of the annular air passage is obtained. The joint 25, 26 is at the left-hand end of the rotor cylinders 1a, 2a.

As shown in Fig. 5 both rotor cylinder members may be conical in the same sense, and obviously they may be both conical in opposite senses.

In the arrangement illustrated by Fig. 6, furthermore, the disconnectable joint between flanges 25a and 26a is nearly in the centre of the length of the rotor members 1c and 1d, and 2d, whereby the greater flexibility as regards changes of blade design from stage to stage can be achieved all as hereinbefore set forth. It will be noticed in Fig. 6 that the outer rotor part 1c is truly cylindrical as is also the right-hand end, beyond the flange joint, of the inner rotor member 2d, whilst the conicities of the member 1d and the left-hand part of the member 2d are

of opposite sense. But it will be appreciated, as hereinbefore set forth, that considerable latitude in these respects is permissible, within limits.

In Fig. 7 is shown an arrangement generally similar to that shown in Fig. 6, except that the inner rotor member also is formed in two sections 2e and 2f having flanges 29 and 30 respectively which can be non-permanently secured together (but which must be secured before assembly), whereby even greater flexibility is permissible in the design of the blading along the stages as governed by the limitations hereinbefore set.

Fig. 8 shows an arrangement which in principle differs only from the arrangements shown in the preceding figures in the respects that, first, the end ring 27a is riveted (or may be welded) at 27b to the left-hand end of the outer cylinder 1g, whilst, secondly, the respective driving shafts 23a and 24a of the rotors 1g, 27a and 2g are in axial alignment.

The arrangement shown in Fig. 9 differs from that shown in Fig. 8 in that the outer rotor 1g, 27a is carried on a shaft 23b whilst the inner rotor 2g is carried on a sleeve shaft 24b, between which and the shaft 23b are the bearings 31. At the left-hand end of the machine is a fixed structure 32 which may be connected through radial webs or fixed guide blading 33 with a fixed casing 34 enclosing the rotational parts of the machine, whilst at the right-hand end of the latter is a stationary structure 35 which may be similarly connected by radial webs or fixed guide blading 36 with a member 37 non-permanently jointed at flanges 38 with the right-hand end of the casing 34. Between a sleeve portion of the stationary structure 35 and the sleeve bearing 24b are bearings 39, whilst a bearing 40 is provided between a sleeve portion of the member 32 and the left-hand end of the shaft 23b.

In the arrangement shown in Fig. 10 there are two tiers of multi-stage blading, the blading of the inner tier A being contra-rotational and conveniently turbine blading, having the two contra-rotational rotor cylinders 41 and 42, the inner rotor 41 of which is fixed to a power shaft 43 extending axially from the machine, whilst the other rotor member 42 of this turbine is combined with, and thus drives, the rotational blading of the outer tier B, which may be that of a compressor or supercharger or similar machine, having alternate rows of outer blading projecting radially inwards from a stationary outer casing 44. It will be appreciated that the rotor cylinder 42 thus has blading projecting radially outwards as well as blading projecting radially inwards. Said rotor 42 may have its left-hand end row of inner blading provided with a foundation ring 45 connected through a "swan-neck" or other flexible member 46 to a disc 47 rigid with a shaft 48 mounted in ball bearings 49 carried in a stationary sleeve 50, which may be in turn carried by a fixed disc or diaphragm 51 connected through the inner and outer tiers of blading at the extreme left-hand end of the machine to the casing 44. Similarly the shaft 43 may be mounted in bearings 52 carried in a stationary sleeve 53 connected through a disc 54 supported through the inner and outer tiers of fixed guide blading or radial webs with the member 55 bolted by flanges to the right-hand end of the casing 44.

The arrangement shown in Fig. 11 differs, in

the main, from that shown in Fig. 10 in that the blading of both the inner and outer tiers A and B are contra-rotational and the two rotors are located in a fixed outer casing 56, associated with which at each end of the machine are double tiers of fixed guide blading by which the two aligned shafts are carried through their bearings generally in the manner described with reference to Fig. 10. The machine necessarily has three rotors 41, 42 and 44. The latter is drivingly connected with the inner most rotor through a row of double tier rotor blading at the right-hand end of the machine and through an additional swan-neck or other flexible member 48a.

In the contra-rotational arrangement shown in Fig. 12 there are two intermediate rotor cylinders 42a and 42b between the inner and outermost blading tiers A and B. The outermost rotor 44a is connected through the extreme left-hand end blading row of the outer tier B, through the swan-neck member 46b and left-hand blading row of the inner part of the machine and swan-neck member 46c, to the shaft 48. The rotor member 42b is connected at its right-hand end through a swan-neck member 46d through the right-hand row of inner tier blading to the innermost rotor member 41 and to the shaft 43. The two rotor cylinders 42a and 42b may be separated merely by a clearance space. A stationary casing may be provided for the machine, if required, such as shown in Fig. 11 and as described with reference thereto.

It will be appreciated that the feature of the concomitant inter-threading of the blading of the rotors into their operative positions is generally applicable to arrangements involving one, two, three or more tiers of blading and so connected that they form one, but preferably two or more, separate rotors. Each tier of blading may have two or more rows or stages. On the other hand in the case of double tier arrangements such as shown in Figs. 13 and 14, inter-threading may be involved in the inner tier blades, whilst mere juxtaposition of the outer tier blading rows is required, such as when there are only two such rows, which are indicated at IIa and IIb in Figs. 13 and 14, which may be ducted fan stages driven by an exhaust or power turbine in accordance with U. S. application Serial No. 518,167. In Figs. 13 and 14 the inner tier turbine is shown as having only four stages of blading I, II, III and IV, of which it is only necessary that the inner stages II and III of blading shall be arranged for inter-threading. Apart from this the general structure of the arrangement shown in Figs. 13 and 14 of the drawings accompanying the present specification will be generally understood after a perusal of the specification of the U. S. application just above mentioned.

With regard to Figs. 8 to 14, the shape of the fluid passage in longitudinal section is only limited by the restriction concerning tapering rotor drum diameters and by the consideration that in the process of assembly complete rings cannot pass blades which occupy the same annular space. These considerations are in the main similar to those applying in the arrangements shown in Figs. 1 to 7 above described. For instance, considering the shape of the fluid passage in longitudinal section, taking any particular annular passage space and assuming that in separating two rotor members the outer boundary of that space is to be moved to the right relatively to the inner one, then the condition to be met is that neither of the two boundary cylindrical or conical or

flaring surfaces may decrease in diameter from right to left; or vice versa if, in separating, the outer boundary is moved to the left. It will be appreciated that in spite of this restriction freedom is left to make the cross-section of the annular space tapering in either direction as desired.

It is to be understood that the rotor cylinder members, or sections thereof, instead of being continuous integral parts as illustrated in the accompanying drawings, may in either or each rotor be previously built up of blade row sub-sections permanently circumferentially jointed together by rivets or bolts or welds.

I claim:

1. The method of manufacturing a machine of the character specified which includes the steps of assembling a fully bladed member, separately assembling the sections of a second fully bladed member with each section provided with at least one row of blading having such form and pitch that it can be interthreaded with at least one row of blading on said first member, moving the sections of said second member axially toward one another and telescopically with respect to said first member into operative relationship while interthreading the blading of said rows on said sections with rows of blading on said first member, and joining adjacent ends of said sections and thereby maintaining the latter in assembled relationship on said first member.

2. Apparatus of the character described comprising an annular fully bladed member, a second annular fully bladed member divided axially into sections, each of said sections comprising at least one row of blading of such form and pitch that it can be interthreaded with at least one row of blading on said first member, a blade ring additional to at least one of said members, and means for connecting adjacent ends of said sections to maintain the latter in assembled relationship on said first member.

3. Apparatus of the character specified comprising contra-rotational members one within the other and carrying rows of radial blading, internal bearings for rotatably supporting said members, and a blade ring additional to at least one of said members, the blading of said members being of such form and pitch that they may be interthreaded for assembly.

4. Apparatus of the character specified comprising relatively rotatable inner and outer members carrying rows of radial blading, at least one of said members being divided axially into sections at least one of which is conical, and having means for securing them together by a circumferential joint, the blading of said members being of such form and pitch that they may be interthreaded.

5. Apparatus of the character specified comprising relatively rotatable inner and outer bladed members, at least one of said members being divided axially into sections having means for connecting them by a circumferential joint between the ends of said members, and a blade ring additional to at least one of said members, the blading of said members being of such form and pitch that they may be interthreaded by axial movements of said sections of one member toward the center of the length of the other member.

6. Apparatus of the character specified comprising relatively rotatable inner and outer bladed members spaced apart radially to form a passage which converges toward one end thereof, at least one of said members being divided axially into

sections having means for connecting them by a circumferential joint between the ends of said passage, at least one of said sections having a conical boundary wall for said passage, the blading of said members being of such form and pitch that the blading of the sections composing one member may be interthreaded with the blading on the other member by axial movements of said sections toward one another.

10 7. Apparatus of the character specified comprising relatively rotatable inner and outer members carrying radial blading and spaced apart to form a passage between them which converges toward one end thereof, at least one of said members being divided axially into sections having means for connecting them by a circumferential joint between the ends of said passage, the boundary wall of said passage on at least one of said sections being conical, and the diameters of the walls of said passage towards the ends thereof being not greater than the diameters of said walls at said joint, the blading of said members being of such form and pitch that the blading of the sections composing one member may be interthreaded with the blading of the other member by axial movements of said sections toward one another.

8. Apparatus of the character specified comprising relatively rotatable inner and outer bladed members having walls spaced apart radially to form a converging passage between them, at least one of said members being divided axially into sections having means for connecting them by a circumferential joint between the ends of said passage, a wall of one member defining said passage at one side of said joint and a wall of the other member defining said passage at the opposite side of said joint being cylindrical and the walls of said members opposite to the respective cylindrical walls being conical, and the blading of said members being of heights conforming with the shape of said passage and being of such shape and pitch that the blading of the sections composing one member may be interthreaded with the blading of the other member by axial movements of said sections toward one another.

9. Apparatus of the character specified comprising inner and outer relatively rotatable bladed members spaced apart radially to form a passage between them, each of said members being divided axially into sections having means for forming a circumferential joint between their adjacent ends, the boundary wall of said passage on one section of each member being conical and said wall on the other section of the respective member being cylindrical, and the blading of said members being of such shape and pitch that the blading of the sections of one member may be interthreaded with the blading of the sections of the other member.

10. Apparatus of the character specified comprising inner and outer radially spaced relatively rotatable bladed members at least one of which is divided axially into sections, means for forming a circumferential joint to connect the adjacent ends of said sections, the blading of said members being of such shape and pitch that the blading of the sections of one member may be interthreaded with the blading of the other member by axial movements of said sections toward one another and telescopically with respect to said other member, and rings carrying additional blading and having means for securing them to the outer ends of said sections.

11. Apparatus of the character specified com-

prising inner and outer radially spaced relatively rotatable bladed members at least one of which is divided axially into sections, means for connecting adjacent ends of said sections to form a circumferential joint between them, the blading of said members being of such shape and pitch that the blading of the sections of one member may be interthreaded with the blading of the other member by axial movements of said sections toward one another and telescopically with respect to said other member, and supporting elements for said sections carrying additional blading and having means for securing them to the outer ends of the respective sections.

12. Apparatus of the character specified comprising inner and outer radially spaced relatively rotatable bladed members each divided axially into sections having means for connecting their adjacent ends to form a circumferential joint, and means including blade rings carried by one of said members toward its respective ends for rotatably supporting it, the blading of said members being of such shape and pitch that the blading of the sections of one member may be interthreaded with the blading of the sections of the other member.

13. Apparatus of the character specified comprising contrarotational members one within the other and spaced apart radially to form a passage between them, and carrying rows of blading disposed in said passage, the boundary wall of said passage on at least one of said members being conical, internal bearings for rotatably supporting said members, and a blade ring additional to at least one of said members, the blading of said members being of such form and pitch that they may be interthreaded for assembly.

14. Apparatus of the character specified comprising relatively rotatable inner and outer members spaced apart radially to form a passage between them and carrying tiers of radial blading disposed respectively in said passage and radially outwardly from said members, and a blade ring additional to the tier of blading of at least one of said members, the blading of said members disposed in said passage being of such form and pitch that they may be interthreaded for assembly.

15. Apparatus as defined in claim 14, wherein the boundary wall of said passage on one of said members is conical.

16. Apparatus of the character specified comprising relatively rotatable members one within the other and spaced apart radially to form a passage between them, and carrying rows of radial blading disposed in said passage, and at least one row of fan blading carried by each of said members and extending radially outwardly beyond the outer member, and a blade ring additional to the blading in said passage carried by one of said members, said radial blading of said members being of such form and pitch that they may be interthreaded for assembly.

17. Apparatus of the character specified comprising contrarotational members one within the other and carrying rows of radial blading between them and fan blading extending radially outwardly beyond said members, internal bearings for rotatably supporting said members, and a blade ring additional to one of said members, said radial blading of said members being of such form and pitch that they may be interthreaded for assembly.

18. Apparatus of the character specified comprising relatively rotatable inner and outer members spaced apart radially to form a passage between them and carrying rows of radial blading disposed in said passage, shafts for rotatably supporting said members, and a blade ring additional to and connecting one end only of at least one of said members to its shaft, the blading of said members being of such form and pitch that they may be interthreaded for assembly.

JOSEPH STANLEY HALL.
